[57] CLAIM

The ornamental design for towel holder, as shown and described.

DESCRIPTION

FIG. 1 is a perspective view of towel holder showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a reduced perspective view thereof, the broken-line disclosure of a towel being for illustrative purposes only and forming no part of the claimed design.

The bar portion is shown broken-away in some view for convenience of illustration.
